CLAIM

We claim the ornamental design for a display screen with graphical user interface for a clinicograph, as shown and described.

DESCRIPTION

FIG. 1 is a front view of a first image in a sequence for a display screen with graphical user interface for a clinicograph;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof;

FIG. 12 is a front view of a twelfth image thereof;

FIG. 13 is a front view of a thirteenth image thereof;

FIG. 14 is a front view of a fourteenth image thereof; and,

FIG. 15 is a front view of a fifteenth image thereof.

The outermost broken line rectangle illustrates a display screen and forms no part of the claimed design. The broken line showing of the hand illustrates environmental subject matter only and forms no part of the claimed design. The remaining broken lines illustrate portions of the graphical user interface that form no part of the claimed design.

The appearance of the image transitions sequentially between the images shown in FIGS. 1-15, The process or period in which an image transitions to another image forms no part of the claimed design.
